UNITED STATES PATENT OFFICE.

WILLIAM B. SMITH, OF PARKESBURG, PENNSYLVANIA.

INJECTOR FOR LOCOMOTIVE-TENDERS.

1,153,138.

Specification of Letters Patent. Patented Sept. 7, 1915.

Application filed December 31, 1914. Serial No. 879,935.

To all whom it may concern:

Be it known that I, WILLIAM B. SMITH, a citizen of the United States, and a resident of Parkesburg, in the county of Chester and State of Pennsylvania, have invented a new and Improved Injector for Locomotive-Tenders, of which the following is a full, clear, and exact description.

This invention relates to improvements in water scoops for locomotive tenders, and has for an object to provide an improved arrangement with means for actuating these scoops, and for controlling and regulating the water as it enters and leaves the tender.

Another object of the invention is to provide an improved arrangement of means for filling the water tank of a locomotive tender without unnecessary splashing, and while the tender is moving or stationary.

In the accompanying drawings Figure 1 is a side view of a tender with an embodiment of the invention applied thereto; Fig. 2 is an enlarged detailed sectional view through a connection embodying certain features of the invention.

Referring to the accompanying drawings by numerals, 1 indicates an ordinary track between the rails of which is arranged a tank containing water adapted to be used in filling the tender 3, which tender is provided with a tank 4 of any desired construction, and into which projects an overflow pipe 5. Arranged at any convenient point is an inlet pipe 6 which is positioned at a considerable angle, and preferably has the upper end turned so as to discharge the water in an inclined downward direction. Connected with the lower end of the overflow pipe 5 is a pivotally mounted scoop 8 supported by link 9 pivotally connected with bell crank lever 10. The bell crank lever 10 is pivotally mounted at 11 to a suitable bracket 12 which also supports the end of scoop 8. The bell crank lever 10 has pivotally connected therewith at 13 a rod 14 having an extension 15. The extension 15 is pivotally connected to a spring pressed rod 16. Rod 16 extends into the air or steam cylinder 17, and is connected to any suitable form of piston so that when air or steam is turned on to cylinder 17 the rod 16 will be moved against the action of spring 18 and scoop 8 will be elevated. When the cylinder 17 is deprived of pressure spring 18 will move the parts in a reverse direction to that just described, and scoop 8 will con-

sequently be lowered. As the bell crank lever 10 moves for raising and lowering scoop 8 the same will operate connecting rod 40, which rod is connected with the double lever 19 mounted on bracket 21, whereby the scoop 23 will also be raised and lowered. The lower end of lever 19 is pivotally connected to scoop 23. Scoop 23 may be of any suitable type provided the same is journaled in a suitable casing 24 which is supported by bracket 25. The brackets or members 12 and 25 are secured to the tender 3 in any desired manner, as for instance by being bolted thereto. By the arrangement of the rod 14 and associated parts the scoops 8 and 23 will be simultaneously raised and lowered so that the same may act together.

Bolted or otherwise rigidly secured to the casing 24 is a casting 26 which is provided with a plurality of apertured members 27 which act as steam jets and with one or more jets 28 for discharging compressed air into the casting 26. Suitable pipes 29 are connected with jets 27 and a pipe 30 is connected with jets 28. The pipes 29 are all connected with a steam supply pipe 31 which is provided with a controlling valve 32 operated by a suitable mechanism 33, which mechanism may extend to the engineer's cab or any convenient point for easy operation. When the steam is turned on to the pipes 29 the same will be discharged by jets 27 into casting 26. These jets extend in a general upward direction and consequently will produce a suction or rarefaction in the scoop 23, whereby water will be drawn therein when the tender is stationary, and will be forced upwardly through pipe 6 and discharged into tank 4. While the tender is moving the water will naturally enter scoop 23 and the steam jets will force the water up into the tank. In case there is not sufficient power from the steam jets compressed air may be supplied from the air tank 34 for raising the water. Valve 35 for releasing the compressed air may be operated by suitable connecting mechanism 36, which mechanism may extend to any suitable point. It will be noticed that the casting 26 is provided with flanges 38 and 38' so as to be bolted respectively to the casing 24 and to the lower end of pipe 6, as shown in Fig. 1. This section will also be easily applied and removed at any time without disturbing the other parts of the device. It will be evident that steam may be sup-

plied to cylinder 17 through suitable piping and said steam may be regulated by a suitable valve arranged at any convenient point so that the engineer or the fireman may raise and lower the scoops whenever desired.

It will be noted that the overflow pipe 5 is an appreciable distance from the inlet pipe 6, and that the inlet pipe 6 is at an appreciable angle so that the water will not be unduly splashed or agitated as the same enters tank 4. A suitable manhole or entrance member 39 may be provided if desired, the same being normally closed by a suitable cap or cover. The arrangement of the inlet pipe 6 at an angle allows the water to be forced into the tank 4 with a less amount of energy so that water may be taken on at comparatively slow speed as well as high speed. By the arrangement of the steam and air jets water may be taken on while the tender is standing still. From these various arrangements it is evident that under any and all circumstances water may be freely taken on by operating certain parts as heretofore described.

What I claim is—

1. In a device of the character described, the combination with a tank, of an inlet pipe therefor, a pivotally mounted scoop 30 arranged at the lower end of said inlet pipe, power means for raising and lowering said scoop, and jets arranged to discharge into said inlet member, said jets being adapted to guide gaseous matter under pressure into said inlet pipe for raising the water entering said scoop and discharging the same out of the upper end of said inlet pipe.

2. In a device of the character described, an inlet pipe arranged at an appreciable angle to the horizontal, a movable scoop arranged at the lower end of said entrance pipe, a plurality of jets for guiding gaseous matter into said inlet pipe, means for supplying gaseous matter to said jets, and valve mechanism for controlling the gaseous matter supplied to said jets.

3. In a device of the character described,

an inlet pipe, a pivotally mounted scoop, means for raising and lowering said scoop, a tubular member arranged between said scoop and said inlet pipe and connecting said scoop and said pipe, said tubular member being formed with a plurality of apertured projections extending inwardly, whereby the gaseous matter passing through said jets will force water upwardly through said inlet pipe, and means for supplying gaseous matter to said jets.

4. In a device of the character described, an inlet pipe, a plurality of steam jets arranged adjacent the lower end thereof for elevating water in said inlet pipe, a pivotally mounted scoop arranged adjacent the lower end of said inlet pipe, and means for raising and lowering said scoop.

5. In a device of the character described, an inlet pipe, a tubular casting arranged at the lower end of said inlet pipe, said tubular casting being formed with a plurality of jets, means for supplying steam to certain of said jets, means for supplying air under pressure to other of said jets, and a scoop connected with the lower end of said tubular casting.

6. In a device of the character described, an inlet pipe arranged at an appreciable angle to the horizontal, a scoop associated with said inlet pipe, a plurality of jets for guiding gaseous matter into said inlet pipe, means for supplying gaseous matter to said jets, a valve mechanism for controlling the gaseous matter supplied from said jets whereby water entering said inlet member through said scoop will be moved upwardly by the gaseous matter passing through said jets.

In testimony whereof I have signed my name to this specification in the presence of two subscribing witnesses.

WILLIAM B. SMITH.
